UNITED STATES PATENT OFFICE.

CLARENCE W. KINNEY, OF WORCESTER, MASSACHUSETTS.

SIGNALING APPARATUS.

1,122,766.

Specification of Letters Patent. Patented Dec. 29, 1914.

Application filed March 25, 1912. Serial No. 686,154.

To all whom it may concern:

Be it known that I, CLARENCE W. KINNEY, a citizen of the United States, residing at Worcester, in the county of Worcester and Commonwealth of Massachusetts, have invented a new and useful Improvement in Signaling Apparatus, of which the following is a specification, accompanied by drawings forming a part of the same.

10 My invention relates to a device designed to be used in connection with the movable part of a machine for the purpose of giving a signal to indicate the stoppage of the machine or some part thereof connected with 15 the signaling apparatus.

I accomplish the object of my invention through the instrumentality of an electric circuit which is maintained open during the normal movement or operation of the machine with which the signaling apparatus is connected, and I provide means for closing the circuit whenever the movement of the connected machine is stopped.

20 In the accompanying drawings, Figure 1 represents in elevation my signaling apparatus connected with a rotating yarn spool. Fig. 2 is a central vertical sectional view on the plane of the broken line 2—2, Fig. 3, through the axis of the signaling apparatus. Fig. 3 is a sectional view on the plane of the broken line 3—3, Fig. 2.

25 Similar reference characters refer to similar parts in the different figures.

Referring to Fig. 1, 1 denotes a yarn spool 35 carrying a strand of yarn 2 which, in the operation of a machine such as a spinning or twisting machine, is assumed to be withdrawn from the spool in the direction of the arrow 3, thereby imparting a rotary motion 40 to the spool. The spool 1, in the present instance, is journaled upon a spindle 4 held in a bracket 5 forming a part of the fixed framework of a machine such as a spinning or twisting machine. Carried upon the hub 45 of the spool 1 is a belt pulley 6 having a belt connection 7 with a belt pulley 8 upon the shaft of a signaling mechanism embodying my invention, and comprising a rotating drum 9 which, in the present instance, is 50 constructed of two circular disks 10 and 11 of vulcanized fiber, hard rubber, or some similar insulating material.

Attached to the outer sides of the disks 55 10 and 11 are gudgeons 12 and 13 journaled in stands 14 and 15. Attached to the inner sides of the disks 10 and 11 and partially

inserted therein are two steel plates 16 and 17, having the inner sides of their peripheries beveled, as represented at 18 and 19. Between the two disks 10 and 11 is inserted 60 an annular disk 20 of sufficient thickness to provide an open space 21 between the steel plates 16 and 17. The annular disk 20 has a circular opening in the center of slightly less diameter than the diameter of 65 the steel plates 16 and 17. Radiating outwardly from this central opening in the annular disk 20 I form a series of channels 22, and communicating with the outer ends of the channels 22 are short channels 23 70 turned inwardly and at an acute angle to the channels 22. The channels 22 and 23 are formed by cutting entirely through the annular disk 20 so that the inner sides of the disks 10 and 11 form the sides of the 75 channels. In each of the channels I place a steel ball 24 capable of turning freely in the channels.

Each of the steel plates 16 and 17 is electrically connected by wires 25 and 26 with 80 copper bands 27 and 28, held concentrically on but insulated from the gudgeons 12 and 13. The copper bands 27 and 28 rotate with the gudgeons, and in contact with them are brushes 29 and 30 connected with wires 31 85 and 32 which form part of an electric circuit including, in the present instance, a bell 33, or an electric lamp or other suitable signaling means may be substituted for the bell 33.

90 In the operation of my improved signaling apparatus the drum 9 is rotated in the direction of the arrow 34, Fig. 3, whenever rotary motion is imparted to the spool 1 by the withdrawal of the yarn strand 2. 95 As each of the channels 22 is carried beneath the center of the rotating drum, the balls will roll by gravity to the outer ends of the channels 22 into the position shown at 24^a. As the disk rotates carrying the channels 100 upward, the steel balls will roll from the outer ends of the channels 22 through the short channels 23 into the position shown at 24^b. Each of the balls will remain in this position at the inner end of a channel 23 as 105 it passes above the center of the rotating drum. Just before the channels 22 move beneath the center of the rotating drum, the balls occupying the positions shown at 24^b will roll down the inclined sides of the 110 channels 23 into the position shown at 24^c. As soon as the ball has left the position 24^b

and rolled to the outer end of a channel 22 into the position shown at 24^c, gravity will tend to roll the ball down the channel 22 into the position indicated by the broken 5 lines 24^d. When the ball is in the position 24^d, it is in contact with the beveled edges 18 and 19 of the steel plates 16 and 17, thereby completing the circuit and causing the bell 33 to ring. Gravity acts, however, to roll 10 the balls toward the center of the drum only when they are in the positions indicated at 24^c. In order to change the position of the ball from 24^b to 24^d, it is necessary that the ball roll outwardly through the channel 23, 15 be brought to a state of absolute rest at the junction of the channels 22 and 23 and then roll the length of the channel 22. These two movements of the ball plus its period of rest require an appreciable time and can 20 only occur when the drum 9 has ceased to rotate, or is rotated so slowly that the ball has time to complete its movement from the position 24^b to that of 24^d. If the drum 9, however, be rotated by the rotation of the 25 spool 1 at the normal speed of the spool 1, the ball will be carried from a position where it is held by gravity at 24^b to a position where it will be held by gravity at 24^a before it has time to form a contact with 30 the plates 16 and 17. So long as the normal rotation of the spool 1 is maintained, therefore, no electrical contact between any of the balls and the plates 16 and 17 will occur. If, however, by the breakage of the 35 strand 2, the rotation of the spool 1 stops, at least one of the balls contained in the channels will roll into contact with the plates 16 and 17, causing an alarm to be sounded as long as the drum remains at rest, 40 unless the electric circuit is broken by a switch or other known means.

While I have herein shown and described the details of one form of my invention, I do not wish to be limited to such details as 45 it is obvious that certain changes may be made within the scope of the appended

claims without departing from the spirit of the invention; but

Having described my invention, what I claim as new and desire to secure by Letters 50 Patent is:

1. In a signaling apparatus, a rotatable drum, a pair of spaced terminals of an electric circuit held concentrically in said drum, said drum having a series of radially extended grooves leading to said terminals, metallic balls adapted to roll by gravity in said grooves into contact with said terminals as said drum is rotated, said drum also having grooves communicating at acute angles with said first mentioned grooves, whereby the movements of said balls are retarded. 55

2. In a signaling apparatus, a rotatable drum, a pair of spaced terminals of an electric circuit carried by said drum, said drum having a series of radially extended grooves leading to said terminals, and balls adapted to roll by gravity in said grooves into contact with said terminals to complete the 70 electric circuit as said drum is rotated, said drum also having grooves communicating at acute angles with said first mentioned grooves, whereby the movements of said balls are retarded. 75

3. In a signaling apparatus, a rotatable drum, a pair of spaced terminals of an electric circuit carried by said drum, said drum having a series of radially extended grooves leading to said terminals, and members 80 adapted to move by gravity in said grooves into contact with said terminals to complete the electric circuit as said drum is rotated, said drum also having grooves communicating angularly with said first mentioned 85 grooves, whereby the movements of said members are retarded.

CLARENCE W. KINNEY.
